[57] CLAIM

The ornamental design for an above ground pool light,
as shown and described.

DESCRIPTION

FIG. 1 is a right side elevational view of an above
ground pool light showing my new design, the side
panel of the housing being in the open position;

FIG. 2 is a front elevational view thereof;

FIG. 3 is a bottom plan view thereof;

FIG. 4 is a left side elevational view thereof, the right
side panel being in the closed position;

FIG. 5 is a top plan view thereof;

FIG. 6 is a rear elevational view thereof; and

FIG. 7 is a top, front, right side perspective view
thereof.
